[57] CLAIM

The ornamental design for a sand pail toy or the like, as shown.

DESCRIPTION

FIG. 1 is a top perspective view of a sand pail toy or the like showing our new design;

FIG. 2 is a front elevational view thereof;

FIG. 3 is a side elevational view thereof;

FIG. 4 is a top plan view thereof;

FIG. 5 is a bottom plan view thereof; and

FIG. 6 is a cross-sectional view taken along line 6—6 of FIG. 4.

FIG.1

FIG.2

FIG. 3

FIG. 4

FIG. 5

FIG. 6
